UNITED STATES PATENT OFFICE.

WILLIAM BENJAMIN SMITH, OF HOPEVILLE, GEORGIA.

GRAIN-CRADLE.

SPECIFICATION forming part of Letters Patent No. 365,947, dated July 5, 1887.

Application filed October 15, 1886. Serial No. 216,350. (No model.)

To all whom it may concern:

Be it known that I, WILLIAM BENJAMIN SMITH, of Hopeville, in the county of Fulton and State of Georgia, have invented certain new and useful Improvements in Grain-Cradles; and I do hereby declare the following to be a full, clear, and exact description of the invention, such as will enable others skilled in the art to which it appertains to make and use the same.

My invention relates to an improvement in grain-cradles.

In an application for Letters Patent filed October 23, 1885, Serial No. 180,706, entitled "grain-cradles," a cradle was shown and described in which metallic fingers were held in position by means of hollow transverse tubes, through which they were made to pass, and were secured to the scythe by means of rods which extended through the tubes. The snath ends of the fingers were secured to an adjustable plate or bar, by means of which, together with a stay extending from the upper end of the adjustable plate or bar to the snath end of the upper or border rib or finger, the point of the cradle was adjusted.

The object of my present invention is to simplify and lighten the intermediate cross-bar and provide for locking the fingers therein in an easy manner.

A further object is to provide an improved stay which shall afford a more complete adjustment of the series of cradle-fingers, and which shall at the same time be stiff, light, and inexpensive.

With these ends in view my invention consists in certain features of construction and combinations of parts, as will be hereinafter described, and pointed out in the claims.

In the accompanying drawings, Figure 1 is a rear view of a portion of a cradle embodying my invention. Fig. 2 is an enlarged view of a portion of the intermediate cross-bar, and Fig. 3 is a detached view of the stay.

A represents the snath, and B the scythe secured to the lower end of the snath in any well-known or approved manner. A series of fingers, C, preferably formed of wire of suitable size and strength, are held in proper position to receive the stalks of grain as they are severed by the scythe—by three cross-pieces,

D, E, and F, extending at right angles, or nearly so, to the scythe. The piece D consists, preferably, of a light metallic tube provided with round transverse perforations *d*, through which the outer ends of the wire fingers extend, the extreme ends of the fingers being bent over and clinched on the outer side of the tube, as shown at *d'*. A rod, G, extends longitudinally through the tube D and projects beyond the lower end of the tubes in the form of an eye, *g*, through which it is bolted to the scythe, near its point. The upper end of the rod G is preferably threaded and secured to the upper or border finger, H, by means of a nut, *g'*, which forces the border finger H snugly against the end of the tube D, or against an interposed washer, as may be found desirable. The middle cross-piece, E, consists of a thin metallic bar rolled transversely into a semicircular or U-shaped form in cross-section, as plainly shown in Fig. 3. It is provided with round transverse perforations *e* at suitable intervals for the passage of the wire fingers. The portions of the fingers which lie between its sides are bent more or less, as shown at *e'*, to prevent the fingers from slipping longitudinally. The smooth convex side of the piece E is toward the front of the cradle, the open portion being in the back, where it is not liable to become clogged or interfere with the sliding of the straw. The ends of piece E are turned at right angles to the body portion, as shown at *g''*, and perforated to receive bolts I, by which the piece is secured firmly to the scythe at a point one-third of the distance from its heel to its point, (more or less) and to the border finger H. The construction of the piece E renders it strong and light and affords an easy means of locking the fingers within it, dispensing with the rod shown and described in the former application.

The piece F is constructed in a manner quite similar to that described in the former application hereinabove referred to, and consists of a thin bar or plate of metal having its edges turned over to give it strength, and provided with a series of perforations, *f*, for the reception of the snath ends of the fingers. The lower end of the piece F is secured to the snath, preferably by means of the same bolt which

secures the heel of the seythe thereto, and its upper end is secured in adjustment toward and away from the snath by a perforated plate, K, projecting from the snath.

5 The border finger H, hereinbefore referred to, is of heavier construction than the fingers C, and is intended to afford them the necessary support and serve as a means of adjusting them at the desired angle to the scythe and snath. It preferably consists of a thin bar of metal having its edges turned down to increase its strength; but it might be formed of tough wood or of metal having a different shape in cross-section than that shown. It extends 15 quite a considerable distance beyond the upper end of the piece E on the snath side, and its projecting end is connected with the plate K on the snath by the brace and stay L.

The brace and stay L consists of a pair of rods diverging from a bolt, M, which conveniently secures their ends to the plate K, the opposite end of which brace L is an elongated loop, l, located athwart the upper side of the end of the border finger H. A bolt, m, 20 extends through a perforation near the end of the border finger H and through the loop l, and a nut, m', on the end of the bolt, serves to lock the end of the border in any desired adjustment throughout the length of the loop. I 25 find it preferable to insert a washer, n, between the lower face of the nut and the upper side of the loop to effect a more extended bearing and prevent wear. The perforation in the border finger, through which the bolt m extends, might also be made more or less elongated, as shown at o, to enable the loop to be shifted toward and away from the end of the border-finger.

The brace and stay L is preferably formed 30 by providing one end of a rod with an eye to receive the bolt M, and bending the opposite end to form the loop l, and then providing a second rod with an eye to receive the bolt M, and locking its opposite end to the end of the loop l. The said stay and brace might, however, be formed of a single piece having the loop l formed at one end and the opposite end secured to the end of the loop, the rod being bent 35 near the middle to embrace the bolt M, and the loop might also be formed by welding a piece to a rod at the proper part, the ends of the rod extending from the bolt M, as shown, and other slight changes in its construction might be resorted to without departing from the 40 spirit and scope of my invention.

The several adjustments secured by the loop l, elongated slot o, and the series of perforations in the plate K render it a comparatively 45 simple matter to set the fingers at the proper angle to secure the best results in cradling grain which is heavy or light, "lodged," or upright, while the diverging parts of the brace and stay L render it stiff with the use of a minimum weight of metal. The shifting of the 50 bolt M from one perforation to another in the plate K will effect a decided change in the "hang" of the cradle, and the slight varia-

tions are accomplished by the shifting of the bolt m along the loop l, or by shifting the loop bodily toward or away from the end of the border-finger, or by both. The stay-rods P, Q, and R extend, respectively, from the bolt M to the upper end of the cross-piece E, from the bolt m to a point on the cross-piece E, a short distance above the scythe, and from the bolt at the heel of the scythe to the upper end of the piece E, and serve to thoroughly brace the whole.

Having fully described my invention, what I claim as new, and desire to secure by Letters Patent, is—

1. In a grain-cradle, the combination, with a series of fingers, of an intermediate cross bar or piece through which the fingers extend, said cross bar or piece having its edges turned, giving it a U shape in cross-section, substantially as set forth.

2. In a grain-cradle, the combination, with the series of fingers, of an intermediate cross bar or piece through which the fingers extend, said cross bar or piece consisting, essentially, of a thin strip or plate of metal having its edges turned around, giving it a U-shaped cross-section open at the back, substantially as set forth.

3. In a grain-cradle, a cross bar or piece adapted to space and support the fingers, and consisting, essentially, of a thin metallic plate or strip U-shaped in cross-section, and having its lower end turned at right angles, or nearly so, for attaching it to the scythe, substantially as set forth.

4. In a grain-cradle, the combination, with the series of fingers, the snath, the scythe, and the border finger, of the tubular end cross-bar 105 to which the fingers are clinched, the rod extending longitudinally through the tubular cross-bar for the attachment of the scythe and border finger, the semi-tubular intermediate cross-bar with its ends turned at an angle to 110 its body and perforated to receive the securing-bolts, and the bar or plate to which the snath ends of the fingers are secured and by means of which the fingers are adjusted, substantially as set forth.

5. In a grain-cradle, the combination, with a series of fingers secured at the proper distance apart by cross-bars connecting the scythe and border finger, of a stay and brace consisting of two branches diverging from a point of attachment near the snath to the opposite ends of a loop in engagement with the snath end of the border finger, whereby the fingers are adjusted relatively to the snath, substantially as set forth.

6. In a grain-cradle, the combination, with the series of fingers secured by cross-bars to the scythe, the upper or border finger, and the snath, of a two-branch stay and brace secured at one end in adjustment toward and away from the snath, and at the other end to the border finger in lateral adjustment thereto, substantially as set forth.

7. In a grain-cradle, the combination, with

the series of fingers, the seythe, the snath, and the border finger, of a stay and brace secured to the snath in adjustment toward and away therefrom, and to the border finger in adjustment transversely thereto and longitudinally therewith, substantially as set forth.

8. In a grain-cradle, a stay and brace connecting the border finger with the snath, said stay and brace consisting, essentially, of a pair 5 of diverging rods leading from the same point to the opposite ends of an elongated loop attached to the border finger, substantially as set forth.

9. In a grain-cradle, a series of metallic fingers extending through an intermediate semi-tubular cross-bar, and provided with bends in that portion of their length lying between the sides of the cross-bar, for the purpose substantially as set forth. 15

In testimony whereof I have signed this 20 specification in the presence of two subscribing witnesses.

WILLIAM BENJAMIN SMITH.
